ONE PIECE HIGH TEMPERATURE WASHER

CROSS-REFERENCE TO RELATED APPLICATION

This application claims the benefit of provisional application Ser. No. 63/345,625 filed May 25, 2022.

BACKGROUND

The present disclosure is directed to the improved high temperature washer.

During production of airfoils for gas turbine engines the parts are precision ground utilizing computer numerical control (CNC) grinders. CNC grinding machines are machine tools which use a rotating grinding wheel to achieve material removal on a metallic workpiece by means of cutting. The CNC grinding machines utilize oil based coolant.

Cutting fluid is a type of coolant and lubricant designed specifically for metalworking processes, such as machining and stamping. There are various kinds of cutting fluids, which include oils, oil-water emulsions, pastes, gels, aerosols (mists), and air or other gases. Cutting fluids are made from petroleum distillates, animal fats, plant oils, water and air, or other raw ingredients. Depending on context and on which type of cutting fluid is being considered, it may be referred to as cutting fluid, cutting oil, cutting compound, coolant, or lubricant.

The oil based lubricant used in blade fabrication deposits an oily residue on the part after the machining operation. Before the part can be further processed, the part must be cleaned to remove the oily residue and any other contaminants. The oily residue can interfere with certain manufacturing processes that occur after machining. The oily contaminants have precipitated unacceptable levels of scrap, rework and process delays.

Traditional parts cleaning machines have been limited to hot water temperatures below 120 degrees Fahrenheit and presented a variety of safety concerns for equipment operators.

What is needed is an improved parts cleaning machine that operates at water temperatures above 120 F and includes programmable logic controllers that increase the level of safety in the parts cleaning machine.

SUMMARY

In accordance with the present disclosure, there is provided a washer comprising a cabinet defining an interior and an exterior; a washing zone within the cabinet interior; the cabinet having a doorway operatively coupled to the washing zone; a door coupled to the exterior of the cabinet within linear motion guides coupled to the exterior, the door configured to open and close the doorway; a door seal coupled to the cabinet exterior proximate the doorway and operatively coupled to the door for sealing the doorway, the door seal comprising an inflatable bladder fluidly coupled to a pneumatic air system; a clamp located within the washing zone, the clamp configured to secure a part within the washing zone; a wash/air nozzle located within the washing zone and fluidly coupled to a process water system, the wash nozzle configured to direct process water toward the part, the wash/air nozzle fluidly coupled to the pneumatic system, the wash/air nozzle configured to direct air toward the part; a safety controller operatively coupled to the door, the pneumatic system and the process water system; and a process

controller operatively coupled to the door, the pneumatic system, the process water system and the clamp, the process controller configured to wash the part.

A further embodiment of any of the foregoing embodiments may additionally and/or alternatively include the clamp comprises internal passages fluidly coupled to the process water system and pneumatic system, wherein process water is configured fluidly coupled to internal channels of the part and pneumatic system air is configured fluidly coupled to the internal channels responsive to the safety controller and process controller.

A further embodiment of any of the foregoing embodiments may additionally and/or alternatively include the clamp includes a rotary joint that is configured to couple a rotary drive with the clamp, the rotary drive configured to rotate the clamp such that the part is exposed on all sides to the wash nozzle located within the washing zone.

A further embodiment of any of the foregoing embodiments may additionally and/or alternatively include the washer further comprising an actuator coupled to the door, the actuator fluidly coupled to the pneumatic system, wherein the actuator opens and closes the door; and a mechanical brake operatively coupled to the actuator, the mechanical brake configured to prevent the door from moving responsive to the safety controller.

A further embodiment of any of the foregoing embodiments may additionally and/or alternatively include the washer further comprising air pressure sensors comprising a first door seal air pressure sensor and a second door seal air pressure sensor operatively coupled to the door seal, wherein the air pressure sensors are operatively coupled to the safety controller and configured to indicate door seal air pressure.

A further embodiment of any of the foregoing embodiments may additionally and/or alternatively include the washer further comprising a dual channel door switch operatively coupled to the door, the dual channel door switch configured to provide a control signal to the safety controller and indicate door position.

A further embodiment of any of the foregoing embodiments may additionally and/or alternatively include the washer further comprising a water tank located at the interior of the cabinet and fluidly coupled to the process water system and the washing zone; the water tank comprising an oil skimmer fluidly coupled to an oil coalescer.

In accordance with the present disclosure, there is provided a washer comprising a cabinet with a washing zone accessible through a doorway; a door with an inflatable door seal for sealing the doorway, the door seal coupled to a pneumatic air system; a clamp for securing a part within the washing zone; a wash/air nozzle located within the washing zone and fluidly coupled to a process water system and a pneumatic system for washing and drying the part; a safety controller operatively coupled to the door, the pneumatic system and the process water system; and a process controller operatively coupled to the door, the pneumatic system, the process water system and the clamp, the process controller configured to wash the part.

A further embodiment of any of the foregoing embodiments may additionally and/or alternatively include the clamp comprises internal passages fluidly coupled to the process water system and pneumatic system; and wherein the clamp includes a rotary joint that is configured to couple a rotary drive with the clamp.

A further embodiment of any of the foregoing embodiments may additionally and/or alternatively include the washer further comprising an actuator coupled to the door,

the actuator fluidly coupled to the pneumatic system, wherein the actuator opens and closes the door; and a mechanical brake operatively coupled to the actuator, the mechanical brake configured to prevent the door from moving responsive to the safety controller.

A further embodiment of any of the foregoing embodiments may additionally and/or alternatively include the washer further comprising air pressure sensors comprising a first door seal air pressure sensor and a second door seal air pressure sensor operatively coupled to the door seal, wherein the air pressure sensors are operatively coupled to the safety controller and configured to indicate door seal air pressure.

A further embodiment of any of the foregoing embodiments may additionally and/or alternatively include the washer further comprising a dual channel door switch operatively coupled to the door, the dual channel door switch configured to provide a control signal to the safety controller and indicate door position.

A further embodiment of any of the foregoing embodiments may additionally and/or alternatively include the washer further comprising a water tank located at an interior of the cabinet and fluidly coupled to the process water system and the washing zone; the water tank comprising an oil skimmer fluidly coupled to an oil coalescer.

In accordance with the present disclosure, there is provided a process for washing a part with a washer comprising accessing a washing zone located within an interior of a cabinet of the washer securing a part to a clamp positioned within the washing zone; closing a door over a doorway that accesses the washing zone; securing the door with a door seal; preventing the door from opening responsive to signals from air pressure sensors and a door switch; washing the part with process water through at least one of a wash/air nozzle within the washing zone and internal passages within the clamp directed into internal channels of the part; and drying the part with air from a pneumatic system fluidly coupled to the wash/air nozzle directed toward the part and the internal passages within the clamp directed into the internal channels of the part.

A further embodiment of any of the foregoing embodiments may additionally and/or alternatively include the process further comprising securing the door in an open position employing a brake operatively coupled to an actuator coupled to the door and configured to lift the door open.

A further embodiment of any of the foregoing embodiments may additionally and/or alternatively include the process further comprising operatively coupling a safety controller to the door via the air pressure sensors and the door switch, the pneumatic system and the process water system; and operatively coupling a process controller to the door via the air pressure sensors and the door switch, the pneumatic system, the process water system and the clamp, the process controller configured to wash the part.

A further embodiment of any of the foregoing embodiments may additionally and/or alternatively include the process controller is configured with a human machine interface providing engineering control of process parameters.

A further embodiment of any of the foregoing embodiments may additionally and/or alternatively include the process further comprising preventing the actuation of the wash nozzle responsive to failure of the door seal as indicated from at least one of the air pressure sensors and the door switch.

A further embodiment of any of the foregoing embodiments may additionally and/or alternatively include the

process further comprising preventing the actuation of the air nozzle responsive to failure of the door seal as indicated from at least one of the air pressure sensors and the door switch.

5 A further embodiment of any of the foregoing embodiments may additionally and/or alternatively include the process further comprising fluidly coupling a water tank located at an interior of the cabinet to the process water system and the washing zone; and fluidly coupling the water tank comprising an oil skimmer to an oil coalescer.

10 Other details of the high temperature washer are set forth in the following detailed description and the accompanying drawings wherein like reference numerals depict like elements.

BRIEF DESCRIPTION OF THE DRAWINGS

FIG. 1 is an isometric schematic representation of an exemplary part washing machine.

15 FIG. 2 is a front view schematic representation of the exemplary part washing machine.

20 FIG. 3 is a side view schematic representation of the exemplary part washing machine.

25 FIG. 4 is a schematic of the pneumatic system supply for the exemplary part washing machine.

DETAILED DESCRIPTION

Referring now to FIGS. 1 through 4, there is illustrated at 30 FIG. 1 an isometric, at FIG. 2 front and FIG. 3 side views respectively of the exemplary high temperature washing machine or simply washer 10. The washer can include a cabinet 12. The cabinet 12 can include an interior 14 and an exterior 16. The cabinet 12 includes a washing zone 18 within the interior 14.

35 Access to the washing zone 18 is controlled by use of a door 20. The door 20 is configured to protect the operators (not shown) from the thermal hazard of hot process water 22 and energized pneumatic system 24 components within the washing zone 18. The door 20 can be a one inch thick Lexan^{TM} plate or equivalent. The door 20 can be transparent allowing an operator to view the processes within the washing zone 18. The door 20 can be supported on the exterior 16 of the cabinet 12 with linear motion guides 26 located on opposite sides of a doorway 28 that provides access from the exterior 16 into the interior 14.

40 An actuator 30 can be coupled to the door 20. The actuator 30 raises and lowers the door 20 in the linear motion guides 26. In an exemplary embodiment, the actuator can include a pneumatic cylinder 32 energized by the pneumatic system 24. A mechanical brake 34 can be coupled to the pneumatic cylinder 32 for physically securing the actuator 30 to prevent unwanted operation. The mechanical brake 34 can operate to engage the pneumatic cylinder 32 and prevent unwanted door 20 actuation on a loss of air pressure from the pneumatic air system 24. A soft start valve 37 can be utilized in the pneumatic air system 24 along with pressure regulators 39 as seen in FIG. 4, to bring the air pressure on-line.

45 The door 20 can be held open with positive actuation of the actuator 30 by use of air pressure in the pneumatic cylinder 32. The pneumatic cylinder 32 extends to lift the door 20 up and open. The door 20 closes upon retraction of the pneumatic cylinder 32. The mechanical brake 34 can be engaged to prevent the door 20 from dropping with a loss of air pressure. The pneumatic cylinder 32 has continuous pressure in the up or down position locking pneumatic cylinder 32 in place and preventing anyone from being able

to open or move the door **20** at all. If air were to fail the mechanical brake **34** can engage due to the low air pressure alarm initiated responsive to low pressure.

A door seal **36** is located proximate the doorway **28** and configured to engage the door **20**. The door seal **36** expands to seal against the inside surfaces of the door **20** around the doorway **28**. The door seal **36** can include an inflatable bladder **38** that encircles the doorway **28** for a complete watertight seal against the door **20**. The door seal **36** can be energized by the pneumatic system **24**. The door seal **36** also acts to physically restrain the door **20** preventing the door **20** from being opened, especially during operation of the washer **10**. The door seal **36** engages the door **20** with sufficient force to prevent the actuator **30** from raising the door **20** in the linear motion guides **26**. As seen in FIG. 2, the door seal **36** can incorporate a door seal regulator **40** configured to regulate the pneumatic system **24** air pressure delivered to the door seal **36** to maintain the appropriate door seal **36** air pressure. The door seal **20** includes redundant air pressure sensors, a first door seal air pressure sensor **42** and a second door seal air pressure sensor **44**.

A dual channel door switch **46** can be operatively coupled to the door **20** and provide a control signal **47** to a safety controller **48**. The safety controller **48** can be configured as a programmable logic controller (PLC). The programmable logic controller is an industrial computer used to control different electro-mechanical processes for use in manufacturing, plants, or other automation environments. The safety controller **48** continuously monitors the state of input devices and makes decisions based upon a custom program to control the state of output devices. In an exemplary embodiment, the safety controller **48** can prevent or allow the process water **22** to energize/spray upon indication that the first door seal air pressure sensor **42** and the second door seal air pressure sensor **44** indicate the door seal **36** is sealed/inflated in addition to the dual channel door switch **46** indicating that the door **20** is properly positioned down closing the doorway **28**. The redundancy in the instrumentation and controls of the safety controller **48** protects the operator from inadvertent energizing/actuation of the process water **22** with the door **20** improperly positioned. In a practical application, the hot water (up to 180 degrees Fahrenheit) cannot be sprayed in the washing zone **18** without the door being completely sealed and closed.

A clamp **50** can be utilized to hold a part **52**, such as a blade. The clamp **50** can be pneumatic and include a clamp pressure regulator **51**. The clamp **50** secures the part **52** inside the interior **14** proximate the washing zone **18**. The clamp **50** includes internal passages **54** as seen in FIG. 2. The internal passages **54** are fluidly coupled to the process water **22**, providing process water **22** to the internal cooling channels **56** of the part **52**. Process water **22** is given access to the internal cooling channels **56** of the part **52** to remove unwanted debris and/or oil residue. The clamp **50** includes a rotary joint **58** that is configured to couple a rotary drive **60** with the clamp **50**. The rotary drive **60** rotates the clamp **50** to allow for the part **52** to be exposed on all sides to a wash/air nozzle **62** located within the washing zone **18**. The wash/air nozzle **62** is fluidly coupled to the process water **22** as well as the pneumatic system **24**. The wash/air nozzle **62** can propel process water **22** at the external surfaces of the part **52** for removal of debris and oil residue. The wash/air nozzle **62** can propel air at the external surfaces of the part **52** for removal of water **22** debris and oil residue.

The process water **22** and pneumatic system **24** air use the same wash/air nozzle **62**. Process water **22** and pneumatic system **24** air also share the same internal passage **54** to

wash/dry the internal section **56** of the part. This sharing of internal and external plumbing is achieved with a series of high-volume check valves and solenoids. The wash/air nozzle **62** produces an excellent wash pattern with liquid in addition to the air.

The wash/air nozzle **62** can be fluidly coupled to the pneumatic system **24**. The wash/air nozzle **62** is configured to direct high pressure air toward the part **52**. The wash/air nozzle **62** can be configured as air knives. An air knife is a tool used to blow off liquid or debris from products as they travel on conveyors. Air knives are used in manufacturing parts drying, as part of component cleaning. The knife consists of a high-intensity, uniform sheet of laminar airflow. An industrial air knife is a pressurized air plenum containing a series of holes or continuous slots through which pressurized air exits in a laminar flow pattern. The exit air velocity then creates an impact air velocity onto the surface of the part **52**. This impact air velocity can range from a gentle breeze to greater than Mach 0.6 (40,000 ft/min) to alter the surface of part **52** without mechanical contact. Air knives remove liquids, control the thickness of liquids, dry the surface, and remove foreign particles from the part **52** surfaces. Electrical currents from anti-static bars can also be injected into the exit air knife stream to neutralize the static electricity charge on some surfaces. Air knives can be stationary while the part **52** passes through the air velocity air stream. In other circumstances, the part **52** can be stationary and the air knives move (reciprocate or rotate) over the surface of the stationary part **52**.

In an exemplary embodiment, the pneumatic system **24** air can also be fluidly coupled to the internal passage **54** of the clamp **50** and provide air to the cooling channels **56** of the part **52** to dry the part **52** interior.

The process water **22** can include deionized water **66**. The process water **22** can be heated up to 180 degrees Fahrenheit with a heater **67**. The process water **22** can include high temperature solenoids **68** and check valves **70**, shown in FIG. 4, along with water pressure sensors **72** that provide instrumentation and controls inputs for the safety controller **48** and a process controller **74** to operate. The temperature solenoids **68** water pressure sensors **72** and check valves **70** can be installed with redundancy to prevent single failure loss of system control.

The cabinet **12** includes a water tank **76**, as shown in FIG. 3. The water tank **76** serves to collect the process water **22**. The water tank **76** can be double walled and insulated to provide operator protection and prevent unwanted heat transfer losses. The process water **22** can be operated from about 160 degrees Fahrenheit to about 180 degrees Fahrenheit. The tank **76** can include a rear section **78** and a forward section **80**. The tank **76** is configured to flow process water **22** from the rear section **78** to the forward section **80**. The process water **22** can be pumped from the forward section **80** into bottles **82**, such as activated carbon bottles. The process water **22** can also be pumped into mixed bed resin bottles **84** to condition the water **22**. An oil skimmer **86** can be located at the forward section **80**. The oil skimmer **86** can process the captured oil into an oil coalescer **88** via an oil skimmer pump **90**.

In an exemplary embodiment, the safety controller **48** and/or the process controller **74** can include data that may be transmitted to one or more processors **92** (e.g., computer systems having a central processing unit and memory) for recording, processing and storing the data received from sensors **42,44** and the like. Processor **92** may include a general-purpose processor, a digital signal processor (DSP), an application specific integrated circuit (ASIC), a field

programmable gate array (FPGA) or other programmable logic device, discrete gate or transistor logic, discrete hardware components, or any combination thereof. Processor 92 may be in communication (such as electrical communication) with sensors 34, 44, 46 and the like and may be configured to receive input. Processor 92 may receive data 94 about the washer 10 captured and transmitted by the sensor(s) 34, 44, 46 and the like via a communication channel. Upon receiving the data 94, the processor 92 may process data 94 from sensors 34, 44, 46 and the like to determine if safe operating conditions are present in the washer 10.

The safety controller 48 is configured to monitor and control the safety functions of the washer 10. The safety controller 48 is configured to monitor and test safety related devices of the washer 10, including but not limited to low pressure conditions in the pneumatic system 24, safety valves 96 (dual monitored dump valves shown in FIG. 3); door switch 46, two hand no tie down 98 (a control that requires a machine operator to use both hands to actuate the washer 10, helping to insure that the operator's hands are not in a position to be injured by the washer 10); E-stop 100 (E-stop (emergency stop) is a simple, highly visible button designed to shut down operations on heavy and/or dangerous equipment. The E-stop 100 is used to save lives in industrial operations, E-stops shut down equipment immediately); process pressure 72, 102; process temperature, low air pressure and the like. The safety controller 48 along with the various sensors and components can be configured to satisfy a Category 3 Safety machine by use of SIL level 3 Safety Rated components.

The process controller 74 can be configured with a human machine interface (HMI) 104 providing the capacity to allow for engineering control of process parameters. The HMI 104 can display input and output signals 106 utilized for troubleshooting the washer 10. The HMI 104 can include alarm states 108 that can be indicated on the HMI 104. The process controller 74 can be configured to control the water temperature. The process controller 74 can utilize a proportional integral derivative (PID) controller 110 to regulate process variables. The PID controller 110 is an instrument used in industrial control applications to regulate temperature, flow, pressure, speed and other process variables. The PID 110 uses a control loop feedback mechanism to control process variables and is the most accurate and stable controller 110. The process controller 74 can also monitor and control the water conductivity of the process water 22. A UV light 112 can be utilized to control unwanted contamination in the process water 22, such as bacteria.

The disclosed washer includes a technical advantage 50 includes improved system cycle time by 300%.

Another technical advantage of the disclosed washer includes cleaner parts.

Another technical advantage of the disclosed washer includes more reliable operation greatly reducing system 55 down time.

Another technical advantage of the disclosed washer includes the capacity to quickly troubleshoot and maintain the washer.

Another technical advantage of the disclosed washer includes a device with Automation Level Category 3 level of safety.

There has been provided a high temperature washer. While the high temperature washer has been described in the context of specific embodiments thereof, other unforeseen alternatives, modifications, and variations may become apparent to those skilled in the art having read the foregoing 65

description. Accordingly, it is intended to embrace those alternatives, modifications, and variations which fall within the broad scope of the appended claims.

What is claimed is:

1. A washer comprising:
a cabinet defining an interior and an exterior; a washing zone within the cabinet interior; the cabinet having a doorway operatively coupled to said washing zone; a door coupled to the exterior of the cabinet within linear motion guides coupled to the exterior, the door configured to open and close the doorway; a door seal coupled to the cabinet exterior proximate the doorway and operatively coupled to the door for sealing the doorway, the door seal comprising an inflatable bladder fluidly coupled to a pneumatic air system; a clamp located within the washing zone, the clamp configured to secure a part within the washing zone; a wash/air nozzle located within the washing zone and fluidly coupled to a process water system, the wash nozzle configured to direct process water toward the part, the wash/air nozzle fluidly coupled to the pneumatic system, the wash/air nozzle configured to direct air toward the part; a safety controller operatively coupled to the door, the pneumatic system and the process water system; and a process controller operatively coupled to the door, the pneumatic system, the process water system and the clamp, the process controller configured to wash the part.
2. The washer according to claim 1, wherein said clamp comprises internal passages fluidly coupled to the process water system and pneumatic system, wherein process water is fluidly coupled to internal channels of the part and pneumatic system air is fluidly coupled to the internal channels responsive to the safety controller and process controller.
3. The washer according to claim 1, wherein the clamp includes a rotary joint that is configured to couple a rotary drive with the clamp, the rotary drive configured to rotate the clamp such that the part is exposed on all sides to the wash nozzle located within the washing zone.
4. The washer according to claim 1, further comprising: an actuator coupled to the door, the actuator fluidly coupled to the pneumatic system, wherein the actuator opens and closes the door; and a mechanical brake operatively coupled to the actuator, the mechanical brake configured to prevent the door from moving responsive to the safety controller.
5. The washer according to claim 1, further comprising: air pressure sensors comprising a first door seal air pressure sensor and a second door seal air pressure sensor operatively coupled to the door seal, wherein the air pressure sensors are operatively coupled to the safety controller and configured to indicate door seal air pressure.
6. The washer according to claim 1, further comprising: a dual channel door switch operatively coupled to the door, the dual channel door switch configured to provide a control signal to the safety controller and indicate door position.
7. The washer according to claim 1, further comprising: a water tank located at the interior of the cabinet and fluidly coupled to the process water system and the washing zone; the water tank comprising an oil skimmer fluidly coupled to an oil coalescer.
8. A washer comprising: a cabinet with a washing zone accessible through a doorway; a door with an inflatable door

seal for sealing the doorway, the door seal coupled to a pneumatic air system; a clamp for securing a part within the washing zone; a wash/air nozzle located within the washing zone and fluidly coupled to a process water system and a pneumatic system for washing and drying the part; a safety controller operatively coupled to the door, the pneumatic system and the process water system; and a process controller operatively coupled to the door, the pneumatic system, the process water system and the clamp, the process controller configured to wash the part.

9. The washer according to claim 8, wherein the clamp comprises internal passages fluidly coupled to the process water system and pneumatic system; and wherein the clamp includes a rotary joint that is configured to couple a rotary drive with the clamp.

10. The washer according to claim 8, further comprising: an actuator coupled to the door, the actuator fluidly coupled to the pneumatic system, wherein the actuator opens and closes the door; and a mechanical brake operatively coupled to the actuator, the mechanical brake configured to prevent the door from moving responsive to the safety controller.

11. The washer according to claim 8, further comprising: air pressure sensors comprising a first door seal air pressure sensor and a second door seal air pressure sensor operatively coupled to the door seal, wherein the air pressure sensors are operatively coupled to the safety controller and configured to indicate door seal air pressure.

12. The washer according to claim 8, further comprising: a dual channel door switch operatively coupled to the door, the dual channel door switch configured to provide a control signal to the safety controller and indicate door position.

13. The washer according to claim 8, further comprising: a water tank located at an interior of the cabinet and fluidly coupled to the process water system and the washing zone; the water tank comprising an oil skimmer fluidly coupled to an oil coalescer.

14. A process for washing a part with a washer comprising:
accessing a washing zone located within an interior of a cabinet of the washer;
securing a part to a clamp positioned within the washing zone;

5

10

closing a door over a doorway that accesses the washing zone;
securing the door with a door seal;
preventing the door from opening responsive to signals from air pressure sensors and a door switch;
washing the part with process water through at least one of a wash/air nozzle within the washing zone and internal passages within the clamp directed into internal channels of the part; and
drying the part with air from a pneumatic system fluidly coupled to the wash/air nozzle directed toward the part and said internal passages within the clamp directed into the internal channels of the part.

15. The process of claim 14, further comprising:
securing the door in an open position employing a brake operatively coupled to an actuator coupled to the door and configured to lift the door open.

16. The process of claim 14, further comprising:
operatively coupling a safety controller to the door via the air pressure sensors and the door switch, the pneumatic system and the process water system; and
operatively coupling a process controller to the door via the air pressure sensors and the door switch, the pneumatic system, the process water system and the clamp, the process controller configured to wash the part.

17. The process of claim 16, wherein the process controller is configured with a human machine interface providing engineering control of process parameters.

18. The process of claim 14, further comprising:
preventing the actuation of the wash nozzle responsive to failure of the door seal as indicated from at least one of the air pressure sensors and the door switch.

19. The process of claim 14, further comprising:
preventing the actuation of the air nozzle responsive to failure of the door seal as indicated from at least one of the air pressure sensors and the door switch.

20. The process of claim 14, further comprising:
fluidly coupling a water tank located at an interior of the cabinet to the process water system and the washing zone; and
fluidly coupling the water tank comprising an oil skimmer to an oil coalescer.
